United States Patent Office

Des. 209,391
Patented Nov. 28, 1967

209,391

SELF-PROPELLED CART

John F. Allen, ½ Alon, Inc., Municipal Airport,
McPherson, Kans. 67460

Filed Oct. 19, 1966, Ser. No. 4,329

Term of patent 7 years

(Cl. D14—3)

FIG. 1

FIG. 2

FIG. 3

FIG. 1 is a perspective view from the upper left rear of a cart showing my new design; and

FIG. 2 is a right side elevation view of same; and
FIG. 3 is a front elevation view of same.

The dominant features of my design reside in the portions shown in full lines.

I claim:

The ornamental design for a self-propelled cart, substantially as shown and described.
